ROWING DEVICE

Silveo A. Basta, Harry D. Basta, and George C. Spurr, Jr., Detroit, Mich.

Application October 23, 1945, Serial No. 623,980

7 Claims. (Cl. 9—25)

1

The invention relates to improvements in rowing devices as described in the present specification and shown in the accompanying drawings that form a part of the same.

The main object of the invention is to provide means whereby a boat may be propelled in the direction in which the rorer is facing, thus simplifying the directing of the course as well as eliminating the dangers and inconvenience occasioned by backward rowing.

Another object of the invention is to provide simple means for clearing the oars from the water at the end of the rowing stroke and insuring its being re-dipped at the proper angle for the next rowing stroke, without the necessity of feathering which is usually a difficult procedure, especially for inexperienced rowers and often occasions splashing.

A further object of the invention is to make possible the use of shorter oars than have hitherto been used and also to provide for easy removal and replacement of such oars, when desired.

A still further object of the invention is to so distribute the leverage as to make the rowing of a boat so equipped easy and safe.

With the above and other objects in view the invention consists in the novel features of construction, arrangements and combinations of parts described in the present specification and more particularly pointed out in the claims for novelty following.

In describing the invention references will be made to the accompanying drawings, in which:

Figure 1 is a perspective view of our improved rowing device attached to the gunwale of a boat.

Figure 2 is a plan view of the rowlock with the cover removed and the ends of the sectional oar broken away.

Figure 3 is a cross sectional view taken on the line 3—3 of Figure 2.

Figure 4 is a longitudinal sectional view taken on the line 4—4 of Figure 2 with the cover in place.

Like numerals of reference indicate corresponding parts in the various figures.

Referring to the drawings, A indicates the bracket, or cradle, adapted to be secured to the gunwale of the boat and B indicates the rowlock which is adapted to be mounted in the bracket A in such a manner that it can be tilted in either direction laterally of the boat.

The bracket A consists of an elongated strip of metal bent longitudinally intermediate of its width to provide arms or plates 1 and 2 respectively, extending at right angles to one another,

2

the arm 1 being adapted to lie in parallel engagement with the outer side of the gunwale 3 and being provided with bolt openings for the reception of suitable bolts by means of which the bracket may be firmly secured to the gunwale, and the arm 2 extending inwardly across and resting on the top edge of the gunwale. The horizontal arm 2 is turned upwardly at each of its ends to provide upstanding lugs 5 and these lugs are provided with aligned openings 6 for the reception of a bearing pin 7, which latter extends from end to end of the bracket and is preferably provided at one end with a head 8 and at its other end with a cross opening for the reception of a cotter pin 9.

The rowlock B consists of a metal block 10 of a length to loosely fit between the lugs 5 of the bracket A and having its sides 11 converging downwardly from points slightly removed from its top to the transverse centre of the block and having a longitudinal bore 12 adapted to loosely receive the bearing pin 7 whereby the block will be supported by said pin slightly above the top face of the arm 2 so that it can be tilted laterally of the boat in the rowing operation.

The top face of the block 10 is recessed to provide a flat bed 13 extending completely across the block and the walls at the ends of said bed are so formed as to provide opposed endwise extensions 14 of the bed of substantially semi-inverted V-shape in plan, with the apices of such extensions located in the transverse centre of the block. The end walls of the bed 13 are further formed to recede at each side of each extension 14 towards the ends of the block, as at 15, to permit of free movement of the oar sections and to limit the movement of the oars to that best suited to rowing, as will be explained hereinafter.

The top face of the block 10 above the bed 13 is flat and is adapted for the reception of a cover plate 16 and such cover plate and the top face of the block are provided with threaded openings 17 for the reception of screws 18 by means of which the cover plate is secured to the block in spaced relation to the bed 13 to provide a channel accessible from each side of the rowlock.

The oar is formed in two sections, the one section consisting of a metal arm 19 having an opening 20 in the outer end thereof for the reception of a blade 21 and the other section comprising a metal arm 22 having a socket in the outer end to receive a handle 23.

The ends of the arms 19 and 22 opposite to those in which the blade and handle are mounted

are extended into the channel in the rowlock from opposite sides and are linked together in endwise overlapping relation and are further pivoted to the rowlock prior to overlapping by means of pins 24 positioned near opposite edges of the rowlock in the longitudinal centre of the latter and anchored in the opposing faces of the bed 13 and the cover plate 16 whereby movement of the oar handle in one direction will cause movement of the blade section in the same direction.

In order to provide the proper endwise overlapping sliding connection between the arms 19 and 22 one of said arms, herein shown as the arm 19, is reduced to provide a flat tongue 25 and this tongue is provided with an elongated slot 26. The other arm, 22, is bifurcated to embrace said tongue and is provided with a pin 27 extending loosely through the slot 26 in the tongue 25. The pin 27 extends beyond each of the arms of the bifurcated portion of the arm 22 and loosely enters arcuate grooves 28 and 29 provided in the bed 13 and the inner face of the cover plate 16 respectively. If desired the pin 27 may be extended through a bushing 30 carried by the bifurcated portion of the arm 22.

It will thus be apparent that when the handle section of the oar including its holder 22 is moved in one direction it will pivot on its fulcrum 24 causing the portion thereof inwardly of the pivot point to swing in the opposite direction and carry the overlapping end of the other arm with it, with the pin 27 sliding within the slot 26 to permit of the varying endwise relation of the arms, and that as the other arm 19 is pivoted to the block the blade section will be moved in the same direction as the handle section.

Those portions of the arms 19 and 22 from the reduced and bifurcated portions outwardly which swing within the oar housing preferably have their top and bottom sides flattened, as at 31, to conform to the opposing faces of the bed 13 and cover plate 16 and are of such thickness that while they will slide freely between said cover plate and bed they will be held thereby against rotation.

The arms 19 and 22 are provided with openings 32 near their outer ends for the reception of suitable pins (not shown) by means of which the blade and handle sections 21 and 23 respectively may be locked to said arms.

In order that the blade and handle parts 21 and 23 may be kept from turning in their sockets such parts are provided with end recesses 33 and the arms 19 and 22 are provided with interiorly located tongues 34 adapted to enter the recesses in the parts 21 and 23.

It will be apparent that when it is desired to remove the blade and handle sections of the oars, such as when leaving the boat unattended, it is simply necessary to remove the pins from the openings 32 and withdraw the sections, which can readily be re-inserted when desired.

In the operation of the invention the rower sits facing the direction in which the boat is to be rowed and after grasping the handle sections of the oars simply move them towards and away from him, or her, in the usual manner, taking care at the completion of each rowing stroke to tilt the rowlock inwardly by a simple turn of the wrist, and hold same in this position during the return stroke to hold the blade free of the water, and to return the blade to the water for the rowing stroke by tilting the rowlock outwardly. The angular relationship of the inclined sides of the rowlock and the flat horizontal face of the sup-

porting bracket is such that in the rowing stroke the blade will attain the required dip and during the return stroke will be raised the required distance to clear the water. The inclined portions 15 of the end walls of the rowlock will be found to limit the forward and rearward movement of the oar section to that best suited for rowing.

While we have illustrated and described the present preferred form of construction for carrying out our invention, this is capable of variation and modification without departing from the spirit of the invention. We, therefore, do not wish to be limited to the precise details of construction set forth, but desire to avail ourselves of such variations and modifications as come within the scope of the appended claims.

What we claim is:

1. In a rowing device, a rowlock comprising a block having a transverse recess therethrough providing a bed, a cover plate spaced from said bed and with the latter providing a transverse channel, said bed and said cover plate having aligned longitudinally extending arcuate grooves, a pair of oar sections extending into said channel from opposite sides of said block, said oar sections being fulcrumed within said channel for pivotal movement on a horizontal plane, said oar sections having pivotal sliding connection at their inner ends, and a pin providing the connection between the ends of said oar sections, said pin at opposite ends entering the grooves in the bed and the cover plate respectively.
2. A rowing device as set out in claim 1, in which the end walls of said recess are cut away to provide longitudinally aligned substantially semi-inverted V-shaped extensions of said bed.
3. A rowing device as set out in claim 1, in which the end walls of said recess are inclined at each side towards the corresponding ends of the rowlock to regulate the stroke of the oar.
4. In a rowing device, a laterally tiltable rowlock comprising a block having a transverse recess therethrough flanked at each end by upstanding walls, a cover plate on said walls spaced from the bed of said recess, said cover plate and said bed having longitudinally extending aligned arcuate grooves in their opposing faces, an oar comprising a blade section and a handle section fulcrumed in said block at opposite sides of said grooves and extending inwardly across said grooves in overlapping relation, one of said oar sections terminating a flat tongue having a longitudinal slot therein and the other of said oar sections having a bifurcated portion embracing said tongue, and a pin extending loosely through said slot in one oar section and through the bifurcated portion of the other oar section and extending into the grooves in said cover plate and said bed respectively.

5. A rowing device as set out in claim 4, in which said oar sections are flattened on their top and bottom surfaces at the points of entry into said block to conform to the flat opposing faces of said cover plate and said bed to prevent rotation of said oar sections.

6. In a rowing device, a laterally tiltable rowlock comprising a block having a transverse recess in the top surface thereof flanked at each end by upstanding walls, a cover plate secured on said walls spaced from the bed of said recess, said cover plate and said bed having longitudinally extending aligned curved grooves in their opposing faces, an oar comprising a blade holding part and a handle holding part extending

into said recess from opposite sides of said block and overlapping at their ends across said grooves, means providing a pivoted sliding connection for the overlapping ends of said blade and handle holding parts, said means entering said grooves and being movable therein, said blade and handle holding parts being pivoted in said block outwardly of their connection with one another, said blade and said handle holding parts being provided at their outer ends with openings for the 10 reception of a blade and a handle respectively, a blade removably mounted in said blade holding part, and a handle removably mounted in said handle holding part.

7. In a rowing device, a bracket adapted to be 15 secured to the gunwale of a boat, said bracket including a horizontal plate having an upstanding lug at each end thereof, said lugs having longitudinally aligned openings therethrough, a pin adapted to be projected through said openings in said lugs, a rowlock comprising a block adapted to loosely fit between the lugs on said bracket and having an opening extending longitudinally therethrough for the reception of said pin whereby said rowlock will be supported by 20 said pin for lateral tilting movement, the sides of said rowlock being inclined downwardly at the required angle to coact with the top face of said bracket to limit the tilting movement of said

rowlock, a cover plate on said rowlock, said rowlock having a transverse recess beneath said recess providing a bed spaced from said cover plate, said cover plate and said bed being provided with 5 aligned longitudinally extending curved grooves in their opposing faces, a pair of oar sections entering said recess from opposite sides of the rowlock and overlapping one another, means providing a sliding pivotal connection between the overlapping ends of said oar sections, and pivotal means for said oar sections at opposite sides respectively of said grooves whereby movement of one oar section will cause movement of the other oar section in a like direction.
